PRINTING PRESS INKING MEANS

Jack C. Talbert, Denver, Colo.

Application August 9, 1941, Serial No. 406,078

8 Claims. (Cl. 101—338)

This invention relates to means for inking printing presses. Printing presses are at present inked by placing thick, "tacky," printer's ink on a rotary distributing disc or drum from whence it is picked up by inking rollers which roll over the type faces. These rollers are relatively short lived and their replacement is a continuous expense. The thick printer's ink must be washed from the distributing plate and rollers whenever a run is finished or whenever the color is changed.

The principal object of this invention is to provide means for inking the presses which will not require inking rollers and inking discs or drums so that expensive replacements and constant washing is entirely eliminated; and which will allow the use of a quick drying fluid ink which will eliminate the necessity for spray guns and other non-offsetting devices.

Another object of the invention is to provide printing press inking means which will supply the entire area of the type form uniformly with ink as contrasted to the present method wherein the side of the form first contacted by the inking roller is inked heavier than the far side thereof; and in which colors of ink can be quickly changed without any intermediate washing of the press.

Other objects and advantages reside in the detail construction of the invention, which is designed for simplicity, economy, and efficiency. These will become more apparent from the following description.

In the following detailed description of the invention reference is had to the accompanying drawings which form a part hereof. Like numerals refer to like parts in all views of the drawings and throughout the description.

In the drawings:

Fig. 1 is a fragmentary side elevation illustrating a portion of a typical job press of the "Gordon" type with the invention applied thereto;

Fig. 2 is a vertical section of the press of Fig. 1, illustrating it in the partially closed position, with the invention shown in cross section;

Fig. 3 is a front view of a typical ink reservoir as employed with this invention;

Figs. 4 and 5 are enlarged cross sections through the ink reservoir, taken on the lines 4—4 and 5—5, Fig. 3, respectively; and

Fig. 6 is an outline view of a typical cylinder press of the flat bed type with the invention in place therein.

The invention is applicable to any type of press. In the drawings only two types are illustrated, they are the typical job press of the "Gordon" type and a typical cylinder press of the

flat bed type. Regular parts of the former press are designated by numeral as follows: fly wheel 10; cam wheel 11, side arms 12, roller yoke frame 13, roller truck 14, truck runway 15, chase bed 16, chase 17, and platen 18.

In the usual press, an ink disc is supported between the two runways 15. With this invention applied, however, the ink disc is removed and a bracket arm 19 secured in its place. The bracket arm supports an ink reservoir 20 which extends laterally of the press above and forwardly of the chase bed 16.

An elongated reel 21 extends longitudinally of the ink reservoir 20 upon which a flexible inking sheet 22 is wound. The sheet 22 may be of any desired material, a good quality of close woven silk has been found highly satisfactory. The upper edge of the inking sheet 22 is secured to the reel 21 and is wound thereon under the influence of a winding spring 23 which surrounds the reel at one extremity thereof, as shown in Fig. 5.

The lower extremity of the flexible inking sheet is removably secured along the upper edge of the chase bed 16 by means of a cross rod 24 or in any other desired manner. The spring 23 constantly maintaining the sheet 22 taut by urging it to wind about the reel 21. The reel rotates partially submerged in a bath of fluid ink 25 with which the reservoir is partially filled.

The sheet exits through a suitable opening at the front of the reservoir over an idler roll 26 against which it is pressed by means of a wringing roll 27. The pressure of the wringing roll 27 against the sheet is adjusted by means of suitable pressure screws 28. The top of the reservoir is closed and access for filling purposes is had through a suitable hinged lid 29.

The usual press carries a plurality of inking rollers actuated from the roller yoke frame 13. When installing this invention all of these rollers except the forward one are removed. The single remaining roller, illustrated at 30, need not be of any particular construction, in fact, a plain composition or rubber covered roller will serve the purpose.

Operation

As the press is closing, as shown in Fig. 1, the roller 30 travels up the runway 15 out of contact with the flexible sheet 22. As the press opens, the roller yoke frame 13 swings downwardly bringing the roller 30 into contact with the rear of the sheet 22. It then continues

downwardly rolling this sheet against the type faces in the chase 17, as shown in Fig. 2.

As the roller 30 moves downwardly, it unrolls the sheet 22 from the reel 21 and increases the tension in the spring 23. As the press begins to close the roller 30 ascends allowing the sheet 22 to be reeled into the reservoir under the action of the spring 23. It will be noted that the sheet does not move over the type so that there is no wear thereon. It will also be noted that the roller 30 does not contact the type so that it will last indefinitely. To change color it is only necessary to detach the reservoir and sheet from the press and replace them with others carrying the desired ink.

In Fig. 6, the same invention is illustrated applied to a flat bed type of press. In such a press, the form carrying the type travels horizontally beneath the inking rollers.

In applying this invention, the reservoir 20, previously described, is mounted on suitable bracket arms 31 across the tracks of the form, illustrated at 32 in Fig. 6. The flexible sheet 22 is carried around a press roller 33 thence over the form 32 where it is secured at 34 to the traveling bed of the form, indicated at 35. Thus, each time the form moves outwardly from the press to the position of Fig. 6, the sheet 22 will be rolled from its reel, pressed against the type faces and stretched thereon, as indicated in Fig. 6. As the form again enters the press, this sheet travels back around the roller 33 into the inking reservoir 20.

While the invention has been described as an inking medium, it can be used without change for applying water to the printing surface of an offset press by simply placing water in the reservoir 20.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. Means for inking the type faces in a printing press comprising: a reel; a sheet of flexible material attached at its inner extremity to said reel; means for rotating said reel to wind said sheet thereon; an inking reservoir maintaining an ink bath about the wound sheet on said reel to apply ink thereto; means for attaching the outer extremity of said sheet to a printing press adjacent the type faces therein; a roller; and means for moving said roller into contact with the back of said sheet and across the type faces between the point of attachment and said bath so as to roll the sheet over the type faces at each opening cycle of said press.

2. The combination with a printing press of the type having an inking roller which travels across the type faces at each opening movement of said press, of an ink reservoir; an elongated reel member in said reservoir; a sheet of flexible material wound about said reel member; a spring constantly urging said reel to wind said sheet, said sheet being positioned across the path of said roller so that the latter will come in contact therewith to withdraw said sheet from said reel and lay it between said roller and the type faces at each opening movement of said press.

3. The combination with a printing press of the type having an inking roller which travels across the type faces at each opening movement

of said press, of an ink reservoir; an elongated reel member in said reservoir; a sheet of flexible material wound about said reel member; a spring constantly urging said reel to wind said sheet; and means for fixedly securing the outer extremity of said sheet to said press so that it will extend across the path of said roller, whereby the latter will contact and spread the inked sheet over the type faces of said press at each opening movement of the latter.

4. The combination with a printing press of the type having an inking roller which travels across the type faces at each opening movement of said press, of an ink reservoir secured at one side of said type faces; an elongated reel member in said reservoir; a sheet of flexible material wound about said reel member; a spring constantly urging said reel to wind said sheet; and means for fixedly securing the outer extremity of said sheet to said press on the same side of the type faces as the reservoir is secured so that it will extend across the path of said roller, whereby the latter will contact and spread the inked sheet over the type faces of said press during its travel across the type faces at each opening movement of the press, said spring acting to rewind said sheet on said reel as said roller releases the former.

5. An inking device for printing presses of the class having an inking roller which travels downward and upward across a substantially vertical type-holding chase at each opening cycle of the press comprising: an elongated ink reservoir; means for supporting said reservoir above the path of said roller; an inking sheet reel in said reservoir; a flexible inking sheet extending from said reel and from said reservoir downwardly across the path of said roller; and means for securing the outer edge of said sheet to said press above the chase thereon and across the path of and between said roller and said chase so that as said roller approaches said chase it will strike said inking sheet and roll it across and against the type faces in said chase.

6. An inking device for printing presses of the class having an inking roller which travels downward and upward across a substantially vertical type-holding chase at each opening cycle of the press comprising: an elongated ink reservoir; means for supporting said reservoir at one side of the path of said roller; an inking sheet reel in said reservoir; a flexible inking sheet extending from said reel and from said reservoir across the path of said roller; and a rod extending across the press above the chase to which the extremity of said sheet is secured, said rod being positioned on the opposite side of the path of said roller so that the latter in traveling to said chase must engage said sheet intermediate its extremities to withdraw it from said reservoir and roll it against the type faces in said chase.

7. An inking device for printing presses of the class having an inking roller which travels downward and upward across a substantially vertical type holding chase at each opening cycle of the press comprising: an elongated ink reservoir; means for supporting said reservoir above the path of said roller; an inking sheet reel in said reservoir; a flexible inking sheet extending from said reel and from said reservoir downwardly across the path of said roller; means for securing the outer edge of said sheet to said press above the chase thereon so that as said roller approaches said chase it will strike said inking sheet and roll it across and against the type faces in

said chase; and means for rewinding said sheet on said reel when the former is released by said roller.

8. Means for inking the type faces in a printing press comprising: a sheet of flexible material; a reel, the inner extremity of said sheet being attached to said reel; means for rotating said reel to wind said sheet thereon; an ink reservoir immediately below said reel, the wound sheet on

said reel being immersed in ink in said reservoir; means for attaching the outer extremity of said sheet to a printing press adjacent the type faces therein; a roller; and means for moving said roller against said sheet between the latter attaching means and said reel so as to unreel said sheet and roll it against the type faces at each open cycle of said press.

JACK C. TALBERT.
